UNITED STATES PATENT OFFICE.

JOSEPH JAMES PATCHETT, OF HALIFAX, ENGLAND, ASSIGNOR TO JOSEPH WILD & CO., OF NEW YORK, N. Y.

DESIGN FOR A CARPET-PATTERN.

Specification forming part of Design No. 6,006, dated July 23, 1872.

Specification describing a new and original Design for a Carpet, invented by JOSEPH J. PATCHETT, of Halifax, in the county of York, England.

The accompanying photographic illustration fully represents my new design.

This invention relates to a new floral scroll-design for carpets, the scrolls being in sections which resemble the letters **S**, but so arranged that one **S**-scroll appears to grow out of an-

other, as shown, thus producing a pleasant and interesting effect. Tufts of flowers are embraced in the convolutions of the scrolls, as shown, and aid in enriching the design.

I claim as my invention—

The design for a carpet, as shown.

JOSEPH JAMES PATCHETT.
